UNITED STATES PATENT OFFICE.

HARRY WARD, OF NEWARK, NEW JERSEY, ASSIGNOR TO OSCAR E. A. WIESSNER, OF BROOKLYN, NEW YORK.

DESIGN FOR A HEADBOARD OR FOOTBOARD FOR BEDSTEADS.

SPECIFICATION forming part of Design No. 28,369, dated March 8, 1898.

Application filed September 3, 1897. Serial No. 650,540. Term of patent 3½ years.

To all whom it may concern:

Be it known that I, HARRY WARD, a subject of the Queen of Great Britain, and a resident of Newark, in the county of Essex and State of New Jersey, have invented a certain new and useful Design for a Headboard or Footboard for Bedsteads, of which the following is a specification.

This invention relates to a design for a headboard or footboard of a metallic bedstead, and is illustrated in the accompanying drawing, which forms a part of this specification.

The essential features of this design embrace the parts of the headboard or footboard as shown and described with the exception of the mounts and finials at the upper ends of the side posts.

In the drawing the posts of the headboard or footboard are indicated at A. These posts are terminated by the beaded mount B, which in turn is capped by the finial C. The lower ends of the posts A are terminated by a claw and ball, as indicated at D. At the middle of the posts there is a scroll-bordered escutcheon E. Extending from the mount B on one post to that upon the other is a horizontal rail F, having an upwardly curved or arched portion at its middle. At a little distance below the rail F another horizontal rail, as G, extends from one post to the other, and near the lower ends of said posts there is another horizontal rail H, which extends from one to the other.

At the junction of the rails G and H with the posts there is located a plate bearing a heart-shaped escutcheon I, from the apex of which diverge projections separated by circles.

A vertical rod, as J, extends from the middle of rail H to the middle of rail G, and a short vertical rod, as J', extends from the middle of rail G to the middle of rail F, where it is terminated in a beaded mount K. Vertical rods, as L, also extend from the rail H to the rail G and have in alinement therewith and extending to the rail F a short rod terminated by a mount K'. Opposite these mounts, on the upper side of rail F, are spheres or balls M.

Upon the rods L, slightly below their middle and also at their junction with the rail G, 50 are triangular-shaped plates N, from the lower sides of which diverge several oblong figures, between which are circles. From the upper sides of the triangles arise recurved leaves O. A like plate, as N, with similarly-recurved leaves O, is also mounted upon the upper end of the rod J', the leaves touching the arched portion of the rail F. The leaves O, also at the upper ends of the rods L, touch the rail F.

Springing from the junctions between the 60 rails G H and the posts A, in a manner to bisect the angles between them, are curved stems, as P, which are terminated by recurved leaves Q.

Like stems and leaves P' Q' spring from a 65 common point on the rod J slightly below its center and extend radially into contact with vertical rods R, which extend parallel to the rod J from the rail H to the rail G. Like rods R also extend from the rail H to the rail G 70 adjacent to the posts A and are touched by the leaves Q.

At the origin of the stems P' there is a scalloped rosette S, having at its center a circle from which lines radiate to the intersection 75 of the scallops.

Upon the rod J, between the stems P', are small recurved leaves connected by a scalloped plate. At the junctions between the vertical rods J, L, and R and the horizontal 80 rails H and G are located heart-shaped escutcheons T, having circles in their centers and diverging protuberances about their apexes, between which protuberances are small circles. 85

What I claim as my invention is—

The design for a headboard or footboard of a bedstead, substantially as herein shown and described.

Signed at New York, in the county of New 90 York and State of New York, this 27th day of August, A. D. 1897.

HARRY WARD.
